UNITED STATES PATENT OFFICE.

GUSTAVE A. OVESON, OF INTERNATIONAL FALLS, MINNESOTA.

GARBAGE-INCINERATOR.

1,132,790.

Specification of Letters Patent. Patented Mar. 23, 1915.

Application filed June 10, 1914. Serial No. 844,247

To all whom it may concern:

Be it known that I, GUSTAVE A. OVESON, a citizen of the United States, residing at International Falls, in the county of Koochiching and State of Minnesota, have invented new and useful Improvements in Garbage-Incinerators, of which the following is a specification.

This invention relates to improvements in garbage incinerators and has particular application to a garbage burning furnace wherein the heating chamber is disposed below the waste receiving chamber.

In carrying out the present invention, it is my purpose to provide a garbage incinerator wherein the garbage or waste receiving chamber will be constructed in such manner that the waste matter will be effectively consumed and wherein the heating chamber will be disposed below the garbage chamber and so formed as to enable the maximum heat thereof to be delivered to the garbage chamber.

It is also my purpose to provide an incinerator of the class described wherein the heating chamber and garbage receiving chamber will be so formed and correlated as to enable the garbage to be effectively heated in the minimum time and with the least consumption of fuel.

With the above and other objects in view, the invention consists in the construction, combination and arrangement of parts hereinafter set forth in and falling within the scope of the claims.

In the accompanying drawings: Figure 1 is a view in front elevation of a garbage incinerator constructed in accordance with the present invention. Fig. 2 is a fragmentary vertical sectional view therethrough. Fig. 3 is a cross sectional view of the same. Fig. 4 is a perspective view of a detail of the invention.

Referring now to the drawings in detail, 15 1 designates a casing which, in the present instance, is circular in cross section. This casing is formed interiorly to provide a garbage receiving chamber 2 and the fire chamber 3 below the garbage receiving chamber. 50 The garbage receiving chamber 2 is preferably oval-shaped and has the relatively large end forming the bottom thereof, while

the fire chamber 3 below the chamber 2 extends across the casing and has the opposite side walls converging upwardly and merging into the bottom of the chamber 2 approximately centrally thereof. The opening establishing communication between the chambers 2 and 3 is substantially rectangular as illustrated in Fig. 3 and is relatively small as compared with the base or bottom of the fire chamber. In this instance, the casing 1 is formed of brick and lime mortar mixed with Portland cement, while the fire and garbage chambers are lined with fire brick disposed in fire clay.

A suitable form of grate 3' is placed across the opening between the fire and garbage chambers and serves to support the waste matter within the chamber 2 and act to break up the gases issuing from the fire chamber so that such gases will pass around the waste material and heat the walls of the upper chamber so that the gases from the waste matter in the garbage chamber will be distilled off from such material and be consumed. It will be noted that this grate may be constructed from old scrap iron such as pipe, odd castings and the like and is therefore inexpensive in construction and capable of being replaced at practically no cost.

Secured to the upper end of the casing 1 and closing the upper extremity of the oval-shaped waste receiving chamber 2 is a hood 4 constructed of any suitable material. In the present instance, this hood is frustoconical in shape and connected with the relatively small end thereof and projecting upwardly therefrom is an outlet flue or stack 5. This flue is composed of a number of sections 6 secured together end to end in axial alignment and the joint at the confronting ends of the sections is preferably turned so that suitable rust preventing fluid may be introduced into the stack. Mounted upon the upper end of the stack 5 is a spark arrester in the form of a cylindrical body 7 composed of wire mesh and having the upper extremity thereof provided with a hinged cover or cap 8 also constructed of wire mesh.

The hood 4 is formed with an opening 9 by means of which the waste matter may be

dumped into the garbage chamber 2 and hinged to the opposite side walls of the opening are doors 10, 10 capable of swinging movement to open and closed positions and having the confronting edges thereof adapted to overlap when closed and provided with a latch 11. Formed in the casing 1 adjacent to the lower end of the chamber 2 and immediately above the opening 12 between such chamber and the chamber 3 is an opening 12 by means of which the waste matter within the chamber 2 may be raked or agitated, and disposed at the opposite sides of the opening 12 are vertical guides 13 within which is slidably mounted a door 14 adapted when in lowered position to close the opening 12 and when in elevated position to uncover such opening.

Formed in the casing 1 below the opening 12 and at one end of the fire chamber 3 is an opening 15 and disposed at the opposite sides of the opening 15 are vertical guides 16 within which is mounted for sliding movement a door 17 adapted to be elevated to uncover the opening 15 and lowered to cover such opening. The doors 14 and 17 are preferably perforated as at 18.

In the present instance, the mechanism for elevating each door 14, 17 to uncover the particular opening comprises a cable 19 extending upwardly toward the upper end of the casing and trained over a guide sheave 20 and thence extended downwardly and having the lower end thereof formed with annular beads suitably spaced apart and adapted to enter a fork 21. Projecting outwardly from the hinged end of the cap 8 is an arm 22 connected with the outer extremity of the arm and depending therefrom is a cord or chain 23 having the links at the lower end thereof adapted to interchangeably engage a fork 24 similar in construction to the fork 21 and disposed adjacent to the latter.

45 In practice, a fire is built in the fire chamber 3 and the doors 10, 10 swung to open position so that the garbage may be dumped into the waste receiving chamber 2. Succeeding the discharge of the waste matter into the chamber 2 the doors 10 are closed and latched in closed position. Owing to the draft produced by the fire 5, air is drawn through the fire chamber 3 over the burning fuel therein and up through the grate supporting the waste matter within the chamber 2 and as the air passes through the fire chamber the velocity thereof is increased, incident to the side walls of the fire chamber converging upwardly, thereby producing an injector action and as the air is relieved of the influence of the restricted upper end of the fire chamber and discharged into the relatively large end of the oval-shaped garbage receiving chamber, such air expands and passes around and up

the side walls of the chamber 2, thereby effectively consuming all the particles of waste matter within the waste receiving chamber and increasing the temperature of such chamber to a relatively high degree. 10 Succeeding the passage of the air through the garbage receiving chamber, such air and the gases resulting from the consumption of the waste matter are drawn up through the stack 5 and discharged into the atmosphere, the spark arrester on the upper end of the stack serving to prevent the discharge of sparks from the incinerator.

When it is desired to agitate the garbage within the chamber 2 or remove the incinerated matter from such chamber, the door 14 is elevated, while to deliver fresh fuel to the fire chamber 3 and to clean the latter the door 17 is actuated to open position.

From the foregoing description taken in connection with the accompanying drawings, the construction and mode of operation of my improved garbage incinerator will be readily apparent. It will be seen that I have provided a garbage burning furnace wherein the particles of waste matter within the particular chamber are effectively consumed and reduced to ashes.

While I have herein shown and described one preferred form of my invention by way of illustration, I wish it to be understood that I do not limit or confine myself to the precise details of construction herein described and delineated, as modification and variation may be made within the scope of the claims without departing from the spirit of the invention.

I claim:

1. A garbage incinerator comprising a casing having a vertical oval shaped chamber to receive the waste matter and a fire chamber disposed below said first chamber and having upwardly converging side walls and the upper end thereof opening into the lower extremity of said first chamber, a grate interposed between said chambers, a frusto-conical shaped hood seated upon the upper end of said first chamber and closing the latter and formed with a door opening therein, doors closing said opening and capable of swinging movement to open and closed positions, and a stack connected with the relatively small end of said hood and upstanding therefrom.

2. A garbage incinerator comprising a casing having a vertically disposed substantially oval-shaped chamber, to receive the waste matter, and a fire chamber disposed below said first chamber and having upwardly converging side walls and the upper end thereof opening into the lower end of said first chamber, and a grate across the opening between said first-named chamber and said second-named chamber acting to support the waste matter in the first-named

tioned chamber and break up the gases issuing from the fire chamber so that such gases will pass around the waste material and heat the walls of the first-mentioned chamber to distil the gases off from the waste material and consume such distilled gases.

In testimony whereof I affix my signature in presence of two witnesses.

GUSTAVE A. OVESON.
